UNITED STATES PATENT OFFICE.

BELA KORMENDY, OF CLEVELAND, OHIO, ASSIGNOR TO THEODOR KUNDZ, OF LAKEWOOD, OHIO.

RIM FOR STEERING-WHEELS OF AUTOMOBILES.

1,088,990.

Specification of Letters Patent.

Patented Mar. 3, 1914.

Application filed July 17, 1911. Serial No. 338,991.

To all whom it may concern:

Be it known that I, BELA KORMENDY, a citizen of the United States of America, residing at Cleveland, in the county of Cuyahoga and State of Ohio, have invented certain new and useful Improvements in Rims for Steering-Wheels of Automobiles; and I hereby declare the following to be a full, clear, and exact description of the invention, such as will enable others skilled in the art to which it pertains to make and use the same.

This invention relates to improvements in rims for steering-wheels of automobiles.

One object of this invention is to provide a wheel-rim of the character indicated which is exceedingly handsome in appearance.

Another object is to have the wheel-rim simple and durable in construction.

With these objects in view, this invention consists in certain features of construction, and combinations and arrangement of parts hereinafter described, pointed out in the claim, and illustrated in the accompanying drawings.

In the said drawings, Figure 1 is a plan view of a wheel-rim embodying my invention. Fig. 2 is a side view of the rim. Fig. 3 is a central vertical section on line 3—3, Fig. 1, looking in the direction indicated by the arrow. Fig. 4 is a vertical section on line 4—4, Fig. 1, looking outwardly. Fig. 5 is a vertical section on line 5—5, Fig. 1, looking outwardly. Fig. 6 is a bottom plan of the rim, and in this figure a portion of the bottom section of the rim is broken away to more clearly show the construction.

My improved wheel-rim comprises an annular wooden top section A, and an annular wooden bottom section B. The sections A and B are arranged directly oppositely and glued or cemented together in any approved manner. The section A (see Fig. 3) is provided at its bottom and centrally between the inner and outer sides of the wheel-rim with an annular recess *a* arranged substantially concentrically relative to the wheel-rim, and the bottom section B (see Fig. 3) is provided at the top thereof and centrally between the inner and outer sides of the wheel-rim with an annular recess *b* which is substantially concentric relative to the wheel-rim. The recesses *a* and *b* register.

An annular wooden section C composed preferably of tough wood, such, for instance,

as hickory, occupies or engages the recesses *a* and *b* and is arranged substantially concentrically relative to the top and bottom sections A and B and consequently substantially concentrically relative to the wheel-rim. The interior section C of the wheel-rim is glued or cemented in any approved manner to the walls of the recesses *a* and *b*. The said interior section C consists preferably of a single wooden piece 65 bent circularly and halved together at its ends, as at 10 (see Fig. 6), which ends are glued or cemented together in any approved manner.

The top and bottom sections A and B are each shown composed of four segmental wooden pieces of handsome or attractive grain, which pieces are arranged end to end and concentrically relative to the wheel-rim, and *g* in Figs. 1 and 6 indicates the grain 75 of the wood.

x indicates the joint between adjacent pieces of the top section A, and *y* represents the joint between adjacent pieces of the bottom section B, and it will be observed that 80 the joints *y* of the bottom section alternate with the joints *x* of the top section.

Preferably each segmental piece of both the top and bottom sections A and B is provided at one end with a substantially V-shaped recess 12 which extends into the said piece in the direction of the other end of the said piece and is formed between the top and bottom of the said piece and engaged by the adjacent end of the adjacent segmental 85 piece of the same section, and the last-mentioned segmental piece is glued or cemented in any approved manner to the walls of the said recess, so that vertical displacement of adjacent ends of the said segmental 90 pieces is positively prevented.

A not unimportant feature of my invention consists in having each segmental piece of the top and bottom sections A and B cemented to the interior section C which is 100 therefore largely instrumental in retaining all of the segmental pieces of the top and bottom sections in place.

By the construction hereinbefore described it will be observed that my improved 105 wheel-rim is exceedingly durable in construction and handsome in appearance.

What I claim is:

In a wheel-rim of the character indicated, oppositely arranged top and bottom annular 110

2

wooden sections provided with registering annular recesses arranged centrally of and substantially concentrically relative to the wheel-rim, and an interior annular wooden section engaging said recesses and arranged substantially concentrically relative to the top and bottom sections, said interior section being composed of a single circularly bent wooden piece which has its ends cemented together, the top and bottom sections being each composed of several wooden segmental pieces arranged end to end and concentrically relative to the wheel-rim, the segmental pieces of the top section being 15 cemented to the segmental pieces of the bot-

tom section, the joints formed between the segmental pieces of the bottom section alternating with the joints formed between the segmental pieces of the top section, and all the segmental pieces of the top and bottom sections being cemented to the aforesaid interior section along all of the walls of the aforesaid recesses.

In testimony whereof, I sign the foregoing specification, in the presence of two 20 witnesses.

BELA KORMENDY.

Witnesses:

B. C. BROWN,
N. McDONNELL.
